UNITED STATES PATENT OFFICE.

MARTIN W. BRUESHABER, OF CHICAGO, ILLINOIS, ASSIGNOR TO GOSS PRINTING PRESS COMPANY, OF CHICAGO, ILLINOIS.

PRINTING PRESS.

Application filed July 2, 1923. Serial No. 648,958.

The invention relates to printing presses, and more especially to novel and useful improvements in intaglio printing presses.

Objects and advantages of the invention will be set forth in part hereinafter and in part will be obvious herefrom, or may be learned by practice with the invention, the same being realized and attained by means of the instrumentalities and combinations 10 pointed out in the appended claims.

The invention consists in the novel parts, constructions, arrangements, combinations and improvements herein shown and described.

15 The accompanying drawings, referred to herein and constituting a part hereof, illustrate one embodiment of the invention, and together with the description, serve to explain the principles of the invention.

20 Of the drawings:—

Fig. 1 is a side elevation, partly diagrammatic, and with certain parts omitted, of a printing press embodying the invention;

25 Fig. 2 is a fragmentary end elevation, corresponding to the lower left-hand end of Fig 1;

Fig. 3 is a view similar to Fig. 2, but showing a different arrangement of printing cylinders;

30 Fig. 4 is an enlarged transverse vertical section, taken substantially on the line 4—4 of Fig. 2; and

Fig. 5 is an enlarged horizontal fragmentary section, taken on the line 5—5 of Fig. 2.

35 Referring now to the embodiment of the invention illustrated by way of example in the accompanying drawings, a web supply roll 1 is mounted on a carriage 2, having wheels 3 running on a track 4, formed in the bed of the machine. 5 represents an extra paper supply roll, carried on a like carriage 6, mounted on wheels 7, running on a guideway 8, carried by the machine frame. This represents a convenient paper supply, although such supply may be of any known or suitable form so far as concerns the present invention. Only one web of paper is led through the press at a time.

40 The web α is led over any number of suitably positioned guiding rollers 14 and 15, and over the mechanism 16, which is preferably a device for regulating the feed of the web, but is indicated only generally herein as it constitutes in itself no part of the present invention. The web then passes over a

guide roll 17, and goes to impression between the impression cylinder 18 and the intaglio form cylinder 19, constituting the members of a printing couple. The web passes thence over other suitably placed 60 guide rollers 20 and 21, and around a drying cylinder 22. Additional guide rollers 23, 24 and 25 are provided, and preferably a web feed regulating device 26. The web then passes around guide rollers 27 and 65 through the impression between impression cylinder 28 and intaglio cylinder 29 to perfect the web.

The web then passes over a guide roll 30 and around drying cylinder 31, past other 70 suitably placed guide rollers 32, 33, 34, 35 and 36, and past a registering or feed regulating device 37. The web then passes to impression between an impression cylinder 40 and an intaglio cylinder 41 to be again 75 printed. It then passes around a guide roller 42, and around a drying cylinder 43, and then over a series of guide rollers 44, 45, 46, 47, 48, 49 and 50 and thence to a folding 80 mechanism indicated generally by 51.

The foregoing represents one general arrangement of a perfecting or multi-color intaglio press, and so far as the present invention is concerned, this general mechanism may be of any desired known or suitable 85 form.

The present invention is directed to auxiliary printing means designed to print only a portion of the entire area which is printed by the full intaglio cylinder or cylinders. 90 A press embodying the invention is capacitated to print in a supplemental color upon a portion of the design printed by the main cylinders, or to add an impression to the original impression of said cylinders. It 95 is further especially designed to provide means whereby one or more intaglio-printed pages may be changed or substituted without disturbing the remainder of the design which it is desired to perpetuate, and without requiring the removal from the press of the entire main or original cylinder, and re-etching and otherwise preparing such cylinder. A particular portion of the original 100 design may be removed from the main cylinder, and the smaller cylinder be positioned to print the substituted design in the corresponding place on the paper.

In the preferred illustrated embodiment 105 of the invention, one or more narrow width 110

cylinders are provided; they are placed at the left hand end of the press of Fig. 1; in Fig. 2, a half-width cylinder 58 being shown, and in Fig. 3 two quarter-width cylinders 59 and 60 are shown. These respective cylinders are slidably positionable along the corresponding shafts, 61 for cylinder 58, and shaft 62 for cylinders 59 and 60. These cylinders are made to rotate with their shafts by suitable means, such as feathers or splines 63, but leaving the cylinders longitudinally shiftable along their shafts. The cylinders are held in desired position along their shafts by suitable means, such as 15 clamping screws 64.

Thus these partial-length cylinders may be shifted along their respective shafts as desired, the cylinder 58 being shiftable onto either half of the full width web, or may be 20 positioned centrally on its shaft. The quarter cylinders 59 and 60 are shiftable independently of each other onto any desired quarters of a full width web. While narrow webs x' , x^2 and x^3 are shown in Figs. 2 and 3, it will be understood that the device 25 will be ordinarily used with a full-width web x , which has been printed upon by the preceding full-width cylinders. For instance, the cylinders 19 and 29 may be regarded as being of full width and printing upon the full width of the web x , and either the cylinder 58 or the cylinders 59 and 60 may be regarded as printing upon any two quarters, or other parts, of the full-width 30 web. This, as already stated, would be in addition to the printing already made by one of the full-width cylinders, or upon a space or spaces left vacant upon the full-width intaglio cylinders, either originally or by 35 etching it away afterward. These cylinders 58, or 59 and 60, would be placed at the left end of Fig. 1, substantially where cylinder 40 is shown. The cylinder 40 may extend 40 the full width of the web, as in Fig. 2; or a plurality of narrow cylinders 40' may be 45 used, as in Fig. 3.

The inking mechanism in its general features may be of any known or suitable form, and as shown the ink fountains or troughs 50 67, 68 and 69, respectively, are of widths corresponding to the respective intaglio cylinders 58, 59 and 60, although if desired a fountain of the full width of the press may be used.

55 To provide for the positioning of the narrow width inking fountains transversely to the press, and corresponding to the position of the intaglio cylinders, each of these fountains is provided with a channeled bottom, having downwardly extending flanges 70 and 71, which fit over either side of, and 60 are slidable along, a horizontally-disposed guiding bar 73 extending across the press, and upon which the fountain rests. One or 65 more clamping screws 72 may be provided to

maintain the fountain in proper position upon the bar 73. The various inking fountains will be provided with doctor blades 74 or equivalent devices.

Means are provided for vertically variably 70 positioning the ink fountain, and for letting it down from the intaglio cylinders and raising it again thereto. In the embodied form thereof, the respective supporting and guiding bars 73 are provided with dove-tail 75 guide-engaging portions 78 at the ends thereof, these portions sliding within vertically-disposed pairs of guideways 79 and 80, fixed to the machine frame. At either end thereof, each guiding and supporting bar 73 has 80 screw-threaded connection with, and is supported on, vertically disposed screw shafts 81 and 82, respectively, which are journaled in lugs 83 and 84 projecting from the uprights of the machine frame.

Collars 85 and 86 maintain the screw-shafts against longitudinal displacement with respect to their mountings. The screw shafts are provided at their bottom ends, respectively, with beveled gears 87 and 88, 90 which mesh, respectively, with bevel gears 89 and 90. These gears are fixed on a shaft 91, which shaft is journaled in bearings 92 and 93, fixed to and projecting upwardly from the bottom frame plate of the press. 95 Any suitable means for turning the screw shaft 91 may be provided, and a crank handle 94 is shown fixed to one end of the shaft for this purpose.

The invention in its broader aspects is not 100 limited to the specific mechanisms shown and described but departures may be made therefrom within the scope of the accompanying claims without departing from the principles of the invention and without 105 sacrificing its chief advantages.

What I claim is:—

1. An intaglio printing press including in combination a printing couple including a full width intaglio printing cylinder, a plurality of narrow width intaglio cylinders 110 variably positionable across the press relatively to the full width intaglio cylinder and relatively to each other and a corresponding plurality of devices for individually inking the narrow intaglio cylinders, each of which is independently variably positionable across the press.

2. An intaglio printing press including 120 in combination a printing couple including a full width intaglio printing cylinder, a plurality of narrow width intaglio cylinders carried upon a single shaft and variably positionable across the press relatively to the full width intaglio cylinder and variably positionable means for inking the narrow intaglio cylinders.

3. An intaglio printing press including in combination a printing couple including a full width intaglio printing cylinder, a plu- 130

- rality of narrow width intaglio cylinders carried upon a single shaft and variably positionable across the press relatively to the full width intaglio cylinder and relatively to each other and a corresponding plurality of independently and variably positionable inking devices for the respective narrow intaglio cylinders, mounted on a common support extending across the press.
- 5 4. An intaglio printing press including in combination a printing couple including a full width intaglio printing cylinder, a plurality of narrow width intaglio cylinders carried upon and rotated by a single shaft 10 and variably positionable across the press relatively to the full width intaglio cylinder a corresponding plurality of ink fountains for the respective narrow cylinders, and a common support for the ink fountains on 15 which they are variably positionable.
- 10 5. An intaglio printing press including in combination a printing couple including a full width intaglio printing cylinder, a plurality of narrow width intaglio cylinders carried upon and rotated by a single shaft 20 and variably positionable across the press relatively to the full width intaglio cylinder and relatively to each other a corresponding plurality of ink fountains for the respective narrow cylinders and a common support for the ink fountains on which they are independently variably positionable.
- 25 6. An intaglio printing press including in combination a press frame, a printing couple comprising a narrow-width intaglio printing cylinder variably positionable across the press, and an ink fountain for the intaglio cylinder variably positionable across the press movable independently of said intaglio 30 cylinder.
- 35 7. An intaglio printing press including in combination a narrow width intaglio printing cylinder, a narrow width ink fountain
- therefor, devices for variably positioning the cylinder and ink fountain transversely of the press, and means for raising and lowering the ink fountain with respect to the cylinder.
- 45 8. An intaglio printing press including in combination a press frame, a plurality of narrow width intaglio printing cylinders 50 variably positionable across the press, a separate ink fountain for each intaglio cylinder, each variably positionable across the press, and means for raising and lowering the ink fountains.
- 55 9. An intaglio printing press including in combination a press frame, a full width intaglio printing cylinder, a plurality of narrow width intaglio cylinders variably positionable across the press, a corresponding 60 plurality of ink fountains, one for each narrow width intaglio cylinder, each variably positionable across the press, and means for raising and lowering the ink fountains.
- 65 10. An intaglio printing press including in combination a press frame, a plurality of narrow width intaglio printing cylinders 70 variably positionable across the press, a separate ink fountain for each intaglio cylinder, each variably positionable across the press, and means for simultaneously raising and lowering the ink fountains.
- 75 11. An intaglio printing press including in combination a press frame, a full width intaglio printing cylinder, a plurality of narrow width intaglio cylinders variably positionable across the press, a corresponding 80 plurality of ink fountains, one for each narrow width intaglio cylinder, each variably positionable across the press, and means for simultaneously raising and lowering the ink fountains.

In testimony whereof, I have signed my name to this specification.

MARTIN W. BRUESHABER.
